No. 744,446.

PATENTED NOV. 17, 1903.

M. WALKER.
TROLLEY GUIDE.
APPLICATION FILED APR. 3, 1903.

NO MODEL.

UNITED STATES PATENT OFFICE.

MILTON WALKER, OF CAMBRIDGE, MASSACHUSETTS.

TROLLEY-GUIDE.

SPECIFICATION forming part of Letters Patent No. 744,446, dated November 17, 1903.

Application filed April 3, 1903. Serial No. 150,947. (No model.)

To all whom it may concern:

Be it known that I, MILTON WALKER, a citizen of the United States, residing at Cambridge, in the county of Middlesex and State 5 of Massachusetts, have invented new and useful Improvements in Trolley-Guides, of which the following is a specification.

The object of this invention is to provide a device to guide a trolley for electric rail- 10 ways as the same is passing a switch or is passing a switch-plate or any plate used for connecting the ends of two portions of trolley- wire wherein the trolley is for a short dis- tance left without a guide to prevent lateral 15 movement thereof.

The invention consists, in a device of the character described, of a trolley-frog, a trolley-wire fast thereto, and a guide-track located beneath said trolley-wire and adapted to guide 20 the trolley as it is passing from one trolley-track to another through a space between the adjacent ends of said trolley-tracks.

The invention again consists in the combination and arrangement of parts set forth 25 in the following specification, and particularly pointed out in the claims thereof.

Referring to the drawings, Figure 1 is a top plan of a trolley frog and wires with my improved auxiliary guide-track attached thereto. Fig. 2 is a side elevation of the parts 30 illustrated in Fig. 1 with a trolley and guide-roll constructed in accordance with my invention in connection therewith. Fig. 3 is a transverse section taken on line 3-3 of Fig. 2.

Like numerals refer to like parts throughout the several views of the drawings.

In the drawings, 8 is a trolley-frog plate, 9 the main trolley-wire, and 10 a branch trolley-wire fastened to the upper side of said plate in 40 a manner well known to those skilled in the art. Beneath the main trolley-wire 9 and integral with the frog-plate 8 are downwardly-projecting trolley-tracks 11, 12 with a space 13 between their adjacent ends. A trolley 14 is supported

45 upon a trolley-pole 15 and is arranged to rotate upon a pin 16 in a manner well known to those skilled in the art. A guide-roll 19 is journaled to rotate upon a stud 20, fast to an arm 17, pivoted at 18 to the trolley-pole 15, said arm 50 being normally held against the stop-pin 24 by a torsional spiral spring 25, one end of

which is fast to the pivotal stud 18, the other to the trolley-pole 15.

A guide-track plate 21 is fastened by screws 22, 22 to the trolley-frog plate 8 and projects 55 downwardly from one side thereof. Upon the under side of said guide-track plate is a guide-track 23, fast to or integral with said guide-track plate. The guide-track 23 extends longitudinally of the frog-plate 8 beneath the trolley-tracks and across the space 13 between the adjacent ends of said trolley-tracks and is located beneath the main trolley-wire 9 and at one side of and parallel to a vertical median plane extending longitudinally of said main trolley-wire. 60

The operation of the device hereinbefore specifically described is as follows: Assuming the car to be moving in the direction of the arrow, Fig. 2, the guide-roll 19 is in advance of the trolley 14 and will engage the right-hand end of the guide-track 23 before the trolley 14 leaves the main trolley-wire 9, so that as the trolley 14 passes under the track 11 the guide-roll 19 will be in contact with the 75 guide-track 23, and as the trolley is passing from the track 11 to the track 12, during which time it is for a short space without positive guide as ordinarily used, the guide-roll 19 will positively guide said trolley and prevent 80 the same from accidentally leaving its proper course, so that it will be sure to engage with the trolley-track 12 after it has passed the space 13.

Having thus described my invention, what 85 I claim, and desire by Letters Patent to secure, is—

1. In a device of the character described, a trolley, a support therefor, a guide-roll supported upon said trolley-support in advance 90 of said trolley, a trolley-frog, a trolley-wire fast thereto, and a guide-track located beneath said trolley-wire and adapted to engage said guide-roll.

2. In a device of the character described, a trolley-frog, a trolley-wire fast thereto, and a guide-track located beneath said trolley-wire at one side of a vertical median plane extending longitudinally of said trolley-wire. 95

3. In a device of the character described, a trolley-frog, a trolley-wire fast thereto, a guide-track plate fast to said frog and extend-

ing downwardly therefrom, and a guide-track fast to said guide-track plate.

4. In a device of the character described, a trolley-frog comprising in its construction two trolley-tracks with a space between their adjacent ends, and a guide-track located beneath said trolley-tracks adapted to guide a trolley in its passage from one to the other of said trolley-tracks.

10 5. In a device of the character described, a trolley, a trolley-pole, an arm pivoted to said trolley-pole, a guide-roll journaled upon said arm in advance of said trolley, a trolley-frog, a trolley-wire fast thereto, and a guide-track

15 located beneath said trolley-wire and adapted to engage said guide-roll.

6. In a device of the character described, a trolley, a trolley-pole, an arm pivoted to said trolley-pole, a guide-roll journaled upon said arm in advance of said trolley, a trolley-frog, 20 a trolley-wire fast thereto, a guide-track located beneath said trolley-wire and adapted to engage said guide-roll, and a spring adapted to hold said guide-roll in engagement with said guide-track.

25

In testimony whereof I have hereunto set my hand in presence of two subscribing witnesses.

MILTON WALKER.
